United States Patent Office

Des. 230,143

Patented Jan. 29, 1974

230,143

AMBULANCE BODY

Donald H. Cox, Lima, Ohio, assignor to Sheller-Globe
Corporation, Toledo, Ohio

Filed Oct. 27, 1971, Ser. No. 193,239

Term of patent 14 years

Int. Cl. D12—08

U.S. Cl. D12—99

FIG - 2 -

FIG. 3 -

FIG. 4 -

FIG. 1 is a right side elevational view of the ambulance body showing my new design, the opposite side being substantially a mirror image thereof;

FIG. 2 is a top plan view thereof;

FIG. 3 is a rear elevational view thereof; and

FIG. 4 is a front elevational view thereof.

The portions shown in broken lines are included for illustrative purposes only.

I claim:

The ornamental design for an ambulance body, as shown and described.
